UNITED STATES PATENT OFFICE

EUGENE H. RUSTIN AND DANIEL J. IULO, OF BROOKLYN, NEW YORK; SAID EUGENE H. RUSTIN ASSIGNOR OF TWO-THIRDS TO MARIE RUSTIN AND SAID DANIEL J. IULO ASSIGNOR OF ONE-THIRD TO RENA IULO, BOTH OF BROOKLYN, NEW YORK

MUFFLER

Application filed January 8, 1931. Serial No. 507,444.

This invention relates to mufflers for internal combustion engines and is an improvement upon the muffler disclosed in our copending application filed May 2, 1930, Serial No. 449,313.

Like the invention disclosed in the application mentioned, the present invention has for its primary object the provision of a device which may be attached to the exhaust of an internal combustion engine to muffle the sound of the exhaust, and to absorb the exhaust gases, so that little if any gas will reach the atmosphere.

The present invention further has for an object the provision of means to simplify and cheapen the construction of the muffler, and to materially add to its efficiency.

With the above and other objects in view, the invention further includes the following novel features and details of construction, to be hereinafter more fully described, illustrated in the accompanying drawings and pointed out in the appended claims.

In the drawings:

Figure 1 is a vertical longitudinal sectional view illustrating the invention.

Figures 2, 3, 4 and 5 are sections taken respectively on the lines 2-2, 3-3, 4-4 and 5-5 of Figure 1.

Figure 6 is an enlarged fragmentary sectional view through the upper end of the valve cylinder illustrating its communication with the atmosphere.

Referring to the drawings in detail where-in like characters of reference denote corresponding parts, the reference character 10 indicates the casing of the muffler which is provided with a removable top or cover 11, the latter being held in place by bolts or screws

12. Preferably formed integral with the muffler casing is a conduit 13, having one end in communication with an inlet port 14, which is adapted for communication with the exhaust of an engine. The lower inner end of the conduit 13 is in communication with a valve casing 15, through the medium of a short pipe section 16, a check valve 17 being arranged within the casing 15. A removable plug 18 extends through the valve casing 15. Also in communication with the valve

casing 15 is a discharge nozzle 19. This nozzle is closed at its outer end and is provided with spaced discharge openings 20 which are arranged at an angle of ninety degrees with respect to one another and so disposed that exhaust gases passing from the nozzle through these openings will be directed downwardly. The muffler casing 10 is partly filled with water or other suitable liquid, the level of which is indicated at 21, and for this purpose, the casing 10 is provided with a filling opening 22 which is normally closed by a plug 23. A drain cock 24 is in communication with the casing 10 below the liquid level line.

Extending upwardly from the bottom of the casing is a deflector plate 25. This plate extends upward substantially to the liquid level line and as shown in Figure 2 of the drawings, the side edges of the plate terminate short of the side walls of the casing 10.

Arranged within the casing 10 is a pipe or conduit 26. One end of this pipe or conduit is attached to the top 11 as shown at 27, while the opposite lower end of the pipe is attached to the bottom of the casing through the medium of a lug 28 and a screw 29. The lower end of this pipe is closed by a valve 30 which is carried at the outer end of an arm 31. This arm is pivotally mounted as shown at 32 and the valve 30 carries a stem 33 which is freely movable within an opening 34 provided in the arm. A securing nut 35, which is mounted upon the stem 33, acts to hold the parts associated, but this nut is so spaced from the arm 31 as to permit of a slight movement and provide for the perfect seating of the valve 30 against the end of the pipe 26.

The pipe 26 is provided with a partition 36 which terminates short of the lower end of the pipe and divides the pipe into a passage 37 and a passage 38, the adjacent ends of these passages opening into what might be termed a separating chamber 39.

The upper end of the passage 37 is provided with an inlet opening 40, while the upper end of the passage 38 is in communication with one end of a discharge pipe 41, 100

whose other end is in communication with the atmosphere.

The arm 31 is pivotally mounted as shown at 32 between spaced ears 42 which extend 5 from the pipe 26, while also extending from this pipe is a rigid arm 43 whose outer end carries a cylinder 44 within which is positioned a bronze or other bushing 45. Operating axially within the bushing 45 is a rod 10 46 which is bored as indicated at 47 to receive a stationary piston 48, the latter being carried at the lower end of a stem 49 which extends from the upper end of a cap 50. This stem 49 is hollow so as to provide an 15 air passage 51, the upper end of which communicates with a hollow screw 52 which passes through the stem 49 and acts to retain the same in place. The hollow screw 52 further provides a passage which is in communication with a pipe 53 attached to the cap 50 as shown at 54.

The inner end of the passage 51 of the stem 49 communicates with a valve chamber 55 provided in the piston 48, one end of this 25 chamber being closed by a plug 56 which is provided with a restricted opening 57.

The muffler casing 10 is provided with a drain opening 58 which is normally closed by a plug 59, and with apertured ears or 30 lugs 60, by means of which it may be secured in position for use.

Exhaust gases enter the muffler through the port 14 and pass downward through the conduit 13, the valve 17 and downward and outward through the nozzle 19. The gases escaping from the nozzle strike the deflector plate 25 and pass upward through and out of the liquid, rising to the top of the casing 10 and entering the passage 37 through the 35 opening 40. These gases pass downward through the passage 37 and force the valve 30 from its seat, so that water carried into the passage 37 with the gases is separated at this point and passes outward into the muffler 40 casing. The separated gases pass upward through the passage 38 to the atmosphere in a purified state. The parts are so proportioned that compression of air within the hollow rod 46 is just sufficient to balance the 45 operation of the valve 30, the compressed air acting to seat the valve 61 within the valve chamber 55. Upon closing movement of the valve 30, the valve 61 will be exhausted so that sufficient air will be drawn into the rod 50 46 for the next compressing operation.

The lower end of the rod 46 is bifurcated and has mounted therein a roller 62 which bears upon the upper edge of the arm 31, while weights 63 which are carried at the 60 lower end of the rod 46 serve to assist the closing movement of the valve 30.

By reference to the drawings it will be seen that escape of liquid from the muffler will be impossible irrespective of the grade 65 or condition of the road over which a vehicle

equipped with the muffler may be traveling.

The invention is susceptible of various changes in its form, proportions and minor details of construction and the right is herein reserved to make such changes as properly fall within the scope of the appended claims.

Having described the invention what is claimed is:—

1. A muffler for internal combustion engines comprising a casing having an inlet adapted for communication with the exhaust manifold of the engine, the casing being partly filled with a liquid, means having one end in communication with the inlet and its other end submerged within the liquid and having outlet openings to discharge the gases into the liquid, a submerged separating chamber within the casing, means extending above the top of the liquid to receive and direct the gases into the separating chamber, a normally closed pressure opened valve forming one wall of the separating chamber to permit the escape of moisture, means other than gravity for resisting opening of the valve and means to direct dry gases to the atmosphere. 75 80 85 90

2. A muffler for internal combustion engines comprising a casing having an inlet adapted for communication with the exhaust manifold of the engine, the casing being partly filled with a liquid, means having one end in communication with the inlet and its other end submerged within the liquid and having outlet openings to discharge the gases into the liquid, a submerged separating chamber within the casing, means extending above the top of the liquid to receive and direct the gases into the separating chamber, a normally closed pressure opened valve forming one wall of the separating chamber to permit the escape of moisture, and gravity and compressed air means to yieldingly resist opening movement of the valve. 95 100 105 110

3. A muffler for internal combustion engines comprising a casing having an inlet adapted for communication with the exhaust manifold of the engine, the casing being partly filled with a liquid, means having one end in communication with the inlet and its other end submerged within the liquid and having outlet openings to discharge the gases into the liquid, a submerged separating chamber within the casing, means extending above the top of the liquid to receive and direct the gases into the separating chamber, a normally closed pressure opened valve forming one wall of the separating chamber to permit the escape of moisture, and pneumatic means to yieldingly resist opening movement of the valve. 115 120 125

4. A muffler for internal combustion engines comprising a casing having an inlet adapted for communication with the exhaust manifold of the engine, the casing being partly filled with a liquid, means having one end in communication with the inlet and its other 130

- end submerged within the liquid and having outlet openings to discharge the gases into the liquid, a pipe located within the casing and having its lower end submerged within the liquid, a partition extending longitudinally of the pipe and dividing the latter into separate passages, one of said passages having an inlet port in its upper end and the other of said passages being in communication with the atmosphere, said partition terminating short of the lower end of the pipe and providing a separating chamber, a normally closed pressure opened valve forming one wall of the separating chamber to permit the escape of moisture and the escape of gas through one of the passages to the atmosphere, an air cylinder with said valve, and a valved piston within the cylinder for providing an air cushion opposing movement of the valve.
5. A muffler for internal combustion engines comprising a casing having an inlet adapted for communication with the exhaust manifold of the engine, the casing being partly filled with a liquid, means to direct exhaust gases into the liquid, a submerged separating chamber within the casing, means extending above the top of the liquid to receive and direct the gases into the separating chamber, a pivotally mounted arm, a normally closed valve carried by said arm and forming one wall of the separating chamber, a vertically movable arm having one end engaging the pivotally mounted arm to resist opening movement of the latter, and pressure operated means to yieldingly resist movement of the vertically movable arm.
6. A muffler for internal combustion engines comprising a casing having an inlet adapted for communication with the exhaust manifold of the engine, the casing being partly filled with a liquid, means to direct exhaust gases into the liquid, a submerged separating chamber within the casing, means extending above the top of the liquid to receive and direct the gases into the separating chamber, a pivotally mounted arm, a normally closed valve carried by said arm and forming one wall of the separating chamber, a vertically movable arm having one end engaging the pivotally mounted arm to resist opening movement of the latter, said vertically movable arm having an axial bore, a rigid piston extending into said bore to provide compression and yieldingly resist movement of said vertically movable arm, and valve controlled means to provide communication between the bore of the vertically movable arm and the atmosphere.
7. A muffler for internal combustion engines comprising a casing partly filled with liquid and having an inlet adapted for communication with the exhaust manifold of an engine, means connected with said inlet for directing exhaust gases in the liquid, a separating chamber within the casing having its lower end submerged within the liquid, means within said separating chamber communicating with the interior of the casing above the level of the liquid therein, gas outlet means connected with the separator, and valve means normally closing the lower end of the separator and opened by an accumulation of water therein.
8. A muffler of the character described comprising a casing partly filled with liquid and having means therein adapted to be connected with the exhaust manifold of an internal combustion engine for conducting the exhaust gases into and bubbling them through the liquid, a separator located within the casing divided into two compartments one communicating with the interior of the casing above the liquid of the level therein and the other being connected with an outlet leading to the atmosphere, the lower end of said separator being located below the liquid level, and a valve normally closing the lower end of the separator but capable of opening to permit discharge of an accumulation of liquid therein.
- In testimony whereof we affix our signatures.
